UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

No. 868,787.

Specification of Letters Patent.

Patented Oct. 22, 1907.

Application filed March 25, 1904. Serial No. 199,983.

To all whom it may concern:

Be it known that I, OSCAR JUNGGREN, a citizen of the United States, residing at Schenectady, in the county of Schenectady and State of New York, have 5 invented certain new and useful Improvements in Means for Adjusting the Relative Positions of Buckets for Elastic-Fluid Turbines, of which the following is a specification.

The present invention has for its object to provide 10 an improved and simple means for adjusting the positions of relatively movable buckets, whereby the proper clearances may be maintained, and the relation of said parts ascertained.

The present invention is an improvement on the 15 construction shown, described and claimed in my application, Serial Number 154,886, filed April 29, 1903.

In the accompanying drawings, which illustrate one embodiment of my invention, Figure 1 is a partial vertical section of a multi-stage vertical-shaft turbine 20 of the jet type; Fig. 2 is an enlarged detail view of the step bearing and the worm wheel for adjusting it; Fig. 3 is a detail view of an indicating device above the platform to indicate the extent of movement of the shaft and bearing blocks; Fig. 4 is a detail view of a 25 double-acting ratchet for moving the bearing-adjusting means; Fig. 5 is a view showing the feeler or means for ascertaining the position of the wheels of the different stages; and Fig. 6 is a sectional view through the machine showing the construction of the feelers or 30 indicating devices.

1 represents a concrete or other suitable foundation for supporting the sub-base 2. The sub-base is provided with an enlarged central opening to receive the lower end of the step bearing casing, and mounted 35 on the upper surface thereof is a casing 3 which supports the wheel casings and is connected to a condenser or atmosphere as is desired. Situated above the condenser casing or base is a wheel casing 4. The bucket wheels 5 are mounted on a vertical shaft 6 that is supported by the step bearing. Mounted on the periphery of the wheel are rows of buckets 7 and between each two rows of buckets is a more or less complete row of intermediate buckets 8. Between the wheel and intermediate buckets is a small space commonly spoken of 40 as a clearance. This clearance, which changes due to unequal expansion of the parts, and also to load variations, should be as small as possible in order to reduce the leakage.

The vertical shaft is supported by a step bearing 9 45 comprising upper and lower bearing blocks, the upper block being attached to the shaft while the lower block is mounted in a detachable head 10 and is adjustable thereon. The upper block rotates with the shaft

while the lower block is prevented from rotating by the pins 11. The bearing as a whole is mounted in the 55 casing 12, which casing also carries a guide bearing. The casing is provided with a peripheral flange that is bolted to the under side of the condenser casing. Situated directly underneath the lower block of the step is an adjusting screw 13 to which is keyed a worm 60 wheel 14. Extending through the screw is a passage for conveying lubricant under pressure to maintain a film between the blocks. The wheel meshes with a worm 15 that is attached to the horizontal shaft 16. The latter is provided with bearings that are formed in 65 or attached to the cylindrical casing 17. This casing is secured to the detachable head 10 by bolts or other securing means.

In order to prevent longitudinal movement of the worm-carrying shaft, thrust collars 18 are provided at 70 opposite ends of the worm. The shaft 16 passes through the concrete or other foundation and is surrounded by a tube 19 which is embedded in the concrete. At the right-hand end the tube is provided with a head which unites with a similar head attached to the cylindrical 75 casing 17. The left-hand end of the tube is attached to a projection 20 formed on the vertical tubular column 21. The tubular column is situated at one side of the turbine casing and is provided with a suitable enlargement that forms a base. Formed in the column 80 at a point adjacent to the projection is an enlargement for receiving the bevel gears 22. One of the gears is mounted on the horizontal worm shaft 16 while the other is mounted on a vertical shaft 23 that is guided by suitable bearings formed in the column. At the 85 lower end the shaft is supported by a cone bearing 24 also carried by the column. The portion of the column adjacent to the gearing is removable so that the condition of the gears may be observed. Attached to the side of the condenser casing is an iron platform 25, 90 that is supported by brackets 26, upon which the engineer stands while adjusting the position of the step bearing and wheel. The shaft 23 extends above the platform and is provided with a cylindrical casing 27 above which is located a ratchet wheel 28 best shown 95 in Fig. 4. Mounted in the handle 29 for engagement with the ratchet wheel is a double-acting pawl 30 that is held on either side of a central position by a spring-pressed plunger 31. As the handle is moved in one direction or the other, the vertical shaft 23 is rotated 100 forward or backward which imparts a similar movement to the horizontal worm shaft 16. As the worm is rotated in one direction or the other, the worm wheel turns the adjusting screw 13 in a direction to raise or lower the step bearing, which changes the clearance 105 between the relatively movable buckets 7 and 8.

In order to determine the extent of relative movement of the vertical shaft 23 and its associated parts, an indicating device is provided, comprising a pointer 32 and dial 33, best shown in Fig. 3. The pointer is 5 driven through suitable worm gearing by a shaft 34, the latter being mounted in bearings carried by the cylindrical casing 27. Connecting the vertical shaft 23 and the indicator shaft 34 is suitable gearing 35. As the shaft 23 is moved in one direction or another from a 10 central position the pointer 32 will be correspondingly moved from its initial position. The indications on the dial 33 are arbitrary but the divisions should be sufficiently far apart to prevent confusion on the part of the operator. For this reason I prefer to make the 15 pointer 32 relatively long so that a small movement of the supporting and actuating spindle will give a large movement at the outer end.

In Fig. 5 is shown a feeler or indicating device for ascertaining the position of the wheel 5. These feelers 20 comprise a roller 36 that is carried by an arm 37. The arm is attached to a spindle 38 that extends through the turbine casing and is provided with a packing 39 to prevent the escape of fluid around the spindle. The center of the spindle and the axis of the roller are eccentrically disposed. The spindle should be located near that portion of the casing carrying the intermediates, measured in a vertical plane, since it acts as a datum point from which to determine the changes in position 30 of the parts. The changes are due to several causes, 30 of which unequal expansion of the casing and shaft in a given interval of time, and unequal expansion of the upper and lower sides of the wheel due to mean temperature differences are the principal.

The spindle 38 is grooved at 40 where it passes 35 through the packing, and by screwing on the gland nut the packing will enter the grooves and hold the spindle against longitudinal movement. At times the pressure in the stage tends to force the spindle out, while at other times, due to the vacuum, it tends to 40 draw it in. I have found in practice that the packing will not only act as such but also prevent longitudinal movement of the shaft.

Mounted on the outer end of the spindle 38 is a handle 41 by means of which the roller 36 can be moved into 45 or out of engagement with a bucket cover or other moving part of the wheel. Attached to the spindle at a point between the handle and the packing is a long pointer 42 that is adapted to move back and forth over a scale 43. This scale is laid off with arbitrary 50 indications, but is preferably so related with respect to the scale 33 (Fig. 3) that one division corresponds to one division of the second-mentioned scale. By reason of this construction if the pointer 42, when the roller engages the wheel, indicates a deflection from 55 the normal or permissible range of, say, three degrees, the engineer knows that the vertical shaft 23 should be moved until the pointer 32 has traveled three degrees. If the deflection is at the right of the initial position, the shaft 23 should be rotated in one direction, and if at the left it should be rotated in the opposite direction. By means of the feeler the engineer is enabled to determine accurately the position of the wheel and intermediate buckets with respect to each other, and at the same time to ascertain how much,

if any, the proper relation has been disturbed. And 65 by means of the pointer 32 he knows just how much the parts have been shifted. The lower wheel is provided with a similar feeler, but the pointer 42, instead of extending downwardly, extends upwardly toward the pointer for the first-stage wheel. In this manner 70 the two scales are brought close together where they can be observed at a glance. The scales are carried by a piece of angle iron 44 that extends between the flanges on the second-stage wheel casing. The wheel chambers are separated one from the other by a dia- 75 phragm 45 to which is attached on the under side a nozzle 46 for discharging motive fluid to the bucket wheel; the nozzle or nozzles for the first-stage wheel, being farther around, do not show.

From the foregoing it will be seen that all parts of the 80 turbine may vary somewhat with respect to each other, which enhances the difficulty of adjustment. With my improved construction however the parts can be unfailingly moved to their proper position.

I have shown a manually actuated device or motor 85 for adjusting the position of the shaft, but I may substitute therefor an electric motor or other equivalent power device.

In accordance with the provisions of the patent 90 statutes, I have described the principle of operation of my invention, together with the apparatus which I now believe to represent the best embodiment thereof; but I desire to have it understood that the apparatus shown is only illustrative, and that the invention 95 can be carried out by other means.

What I claim as new and desire to secure by Letters Patent of the United States, is:

1. A turbine comprising sets of relatively rotating buckets, a main shaft which carries one set of buckets, a support for the shaft, a means for adjusting the support, an 100 indicating device for indicating the extent of movement of the support and one set of buckets, and a driving connection separated from and driven by the said adjusting means for actuating the indicating device.

2. A turbine comprising sets of relatively rotating buckets, a main shaft which carries one set of buckets, a support for the shaft, a means for adjusting the support, and a feeler which is movable into or out of engagement with a wheel for ascertaining the position of the wheel buckets. 105

3. A turbine comprising sets of relatively rotating buckets, a main shaft which carries one set of buckets, a support for the shaft, a screw for adjusting the support, a vertical column situated at one side of the turbine, a shaft therein, gearing connecting the shaft and the screw, and means for imparting movement to the shaft. 110

4. A turbine comprising sets of relatively rotating buckets, a main shaft which carries one set of buckets, a support for the shaft, a screw for adjusting the support, a vertical column situated at one side of the turbine, a shaft therein, gearing connecting the shaft and the screw, a means for imparting movement to the shaft, and an indicating device that is moved by the shaft for indicating the position of the support. 115

5. A turbine comprising sets of relatively rotating buckets, a main shaft which carries one set of buckets, a support for the shaft, a screw carried by the support for adjusting the shaft, a horizontal shaft, gearing between the shaft and the screw, and a means for driving the shaft. 120

6. A turbine comprising sets of relatively movable buckets, a main shaft which carries one set of buckets, an adjustable support for the shaft, and means for moving the support, comprising a horizontal shaft, a vertical shaft, gearing between the shafts, and a device for imparting movement to the vertical shaft. 125

7. A turbine comprising sets of relatively movable buckets, a main shaft which carries one set of buckets, a support for the shaft, a screw carried by the support for adjusting the shaft, a horizontal shaft, a vertical shaft, gearing between the shafts, and a device for imparting movement to the vertical shaft. 130

7. A turbine comprising sets of relatively movable buckets, a main shaft which carries one set of buckets, a support for the shaft, a screw carried by the support for adjusting the shaft, a horizontal shaft, a vertical shaft, gearing between the shafts, and a device for imparting movement to the vertical shaft. 135

- buckets, a main shaft which carries one set of buckets, an adjustable bearing for supporting the weight of the shaft, a device for raising and lowering the bearing, a column located at one side of the turbine, a shaft mounted therein, means for imparting motion from the shaft to the device, and a lever for moving the shaft.
8. A turbine comprising sets of relatively movable buckets, a main shaft which carries one set of buckets, a means for adjusting the shaft longitudinally, an indicator for showing the position of one set of buckets, and a second indicator which is located adjacent to the first for showing the position of the second set of buckets.
9. A turbine comprising sets of relatively movable buckets, a main shaft which carries one set of buckets, an adjustable bearing for the shaft, a means for raising and lowering the bearing, an indicator moved by said means for showing the position of the bearing, and a second indicating device for showing the relation between the relatively movable buckets.
10. A turbine comprising sets of relatively moving buckets, a main shaft which carries one set of buckets, an adjustable bearing for the shaft, a means for raising and lowering the bearing, and an indicator for showing the position of the bearing, comprising a pointer and dial with gearing between the means and the pointer.
11. A turbine comprising sets of relatively movable buckets, a main shaft which carries one set of buckets, an adjustable bearing for the shaft, connected shafts located at an angle to each other for raising and lowering the bearing, and a double-acting ratchet for imparting movement to the shaft.
12. A turbine comprising sets of relatively movable buckets, a main shaft which carries one set of buckets, an adjustable bearing for the shaft, a horizontal shaft for raising and lowering the bearing, a vertical shaft connected to the horizontal shaft for moving it, a column which surrounds the vertical shaft, a ratchet for moving the vertical shaft, and a platform situated adjacent to the ratchet and column.
13. A turbine comprising sets of relatively movable buckets, a main shaft which carries one set of buckets, an adjustable bearing for the shaft, a screw for moving the bearing, a head for supporting the screw, a worm-wheel on the screw, a worm meshing with the wheel, a support for the worm attached to the head, and a shaft 45 for actuating the worm.
14. A turbine comprising sets of relatively moving buckets, a main shaft which carries one set of buckets, means for adjusting the shaft longitudinally, an indicator moved by the means for showing the extent of movement 50 of the shaft and its buckets, and a feeler for showing the position of the wheel.
15. A multi-stage turbine comprising sets of relatively movable buckets, a main shaft which carries sets of buckets, means for adjusting the shaft longitudinally, 55 an indicator moved by the means for showing the extent of movement of the shaft and its buckets, and feelers for showing the position of the several wheels.
16. A multi-stage turbine comprising wheel and intermediate buckets mounted in separate compartments, in 60 combination with feelers for the separate wheels, and dials for the feelers, which are located in close proximity.
17. A multi-stage turbine comprising wheel and intermediate buckets mounted in separate compartments, in combination with feelers for the separate wheels, pointers 65 attached to the feelers, which extend toward each other, and dials or scales over which the pointers travel.
18. A multi-stage turbine comprising wheel and intermediate buckets mounted in separate compartments, in combination with feelers for the separate wheels, pointers 70 attached to the feelers, which extend toward each other, dials or scales over which the pointers travel, and a support which is common to the dials or scales.
19. In a turbine comprising relatively movable parts and a shaft for supporting one of said parts, the combination of a bearing for supporting the shaft, a casing 75 for the bearing, a head secured to the casing, a screw for supporting the shaft, that extends through the head, a cylindrical support that is attached to the head, a worm wheel attached to the screw, a worm meshing with the 80 wheel and carried by the cylindrical support, and a shaft for driving the worm.
- In witness whereof I have hereunto set my hand this 24th day of March, 1904.

OSCAR JUNGGREN.

Witnesses:

EDWARD WILLIAMS, Jr.,
HELEN ORFORD.
